UNITED STATES PATENT OFFICE.

GEORGE H. HARMAN, OF GLEN RIDGE, NEW JERSEY.

DOUBLE-COMPARTMENT POWDER-BOX.

1,360,739.

Specification of Letters Patent. Patented Nov. 30, 1920.

Application filed July 6, 1920. Serial No. 394,073.

To all whom it may concern:

Be it known that I, GEORGE H. HARMAN, a citizen of the United States, residing at Glen Ridge, in the county of Essex and 5 State of New Jersey, have invented certain new and useful Improvements in Double-Compartment Powder-Boxes; and I do hereby declare the following to be a full, clear, and exact description of the invention, such 10 as will enable others skilled in the art to which it appertains to make and use the same, reference being had to the accompanying drawings, and to characters of reference marked thereon, which form a part of this 15 specification.

The present invention relates, generally, to improvements in cases or boxes adapted to contain face-powders, cosmetics, and the like; and, the invention has reference, more 20 particularly, to a novel construction of double compartment powder-box or case, adapted to hold powders and rouge in the form of compacts or cakes, and of different 25 colors, as, for example, one compact comprising white face powder and the other pink or red rouge.

The invention has for its principal object 30 to provide a very neat, attractive and convenient double compartment box or case of small bulk; the same comprising a pair of shells or body members hinged together so as to mutually close one upon the other, each shell or body member providing a compartment adapted to hold a compact, and being 35 further provided with means for retaining the compacts in place, there being combined in novel mutually connected relation to said shell or body members an intermediate mirror member or plate, which also serves as a 40 partition between the respective compartments when said shells or body members are closed together.

Other objects of the present invention, 45 not at this time more particularly enumerated, will be clearly understood from the following detailed description of the same.

With the various objects of the present invention in view, the same consists, primarily, 50 in the novel construction of double compartment powder-box or case hereinafter set forth; and, the invention consists, furthermore, in the novel arrangements and combinations of the various devices and parts, as well as in the details of the construction 55 of said parts, all of which will be more fully described in the following specification, and

then finally embodied in the claims appended thereto.

The invention is fully illustrated in the accompanying drawings, in which:

Figure 1 is a side elevation of the novel construction of double compartment powder-box or case made according to and embodying the principles of this invention, the same being shown in its closed condition; Fig. 2 60 is a central vertical section through the closed powder-box or case; Fig. 3 is a plan view of said novel double compartment powder-box or case in its opened condition; Fig. 4 is a vertical section, taken on line 4—4 65 in said Fig. 3; and Fig. 5 is a detail vertical section of a portion of the novel powder-box or case illustrating a slightly modified form of intermediate combined mirror and partition member for employment therewith. 70

Similar characters of reference are employed in all of the hereinabove described views, to indicate corresponding parts.

Referring now to said drawings, the reference-character 1 indicates the complete novel 80 double compartment powder-box or case made according to and embodying the principles of the present invention, the same comprising a lower shell or body member 2 and an upper shell or body member 3, the former 85 providing a compact holding compartment 4, and the latter providing a similar compact holding compartment 5. Said respective shells or body members 2 and 3 may be made in any desired form of exterior shape or contour, to provide, when closed together, the 90 desired ornamental effect and appearance.

Said lower shell or body member 2 is provided at its open periphery or mouth with an inwardly off-set vertical flange or rim 6 95 which telescopes into the open end of said upper shell or body member 3, when the latter is moved into closed relation to the former, thus preventing lateral displacement or separation of the said shells or body members when so closed together.

The said shells or body members 2 and 3 are mutually pivoted together, to swing apart one from the other, by means of a hinge member 7, suitably secured to the adjoining sides 105 thereof. The flange or rim 6 of said shell or member 2 is provided, at a point diametrically opposite the hinge connection, with an outwardly pressed catch nosing 8, and, in like manner, the marginal portion of the side 110 wall of said shell or body member 3 is provided with a correspondingly located catch

receiving socket 9, which snaps over said catch nosing 8 when said shells or body members are closed together, to thereby hold the same in their mutually closed relation.

5 One shell or body member, for example, the shell 2, is adapted to hold seated within its compartment 4, a compact 10 comprised of white face-powder, and the other shell or body-member, *e. g.*, the shell 3, is adapted to 10 hold seated within its compartment 5, a compact 11 comprised of rouge or the like.

Each shell or body member is provided in connection with its side walls, and suitably located with reference to the size or thickness 15 of the compacts, with two or more retaining members 12 adapted to project inwardly into their compartments to engage the compacts therein, and to thereby retain the same against accidental displacement from proper 20 seated relation within said compartments.

As shown in the drawings, said retaining members 12, may consist, in one form, of lugs or teats forced outwardly from the inner side wall surface of each shell or body-member 25 to project into their respective compartments so that the compacts may be sprung downwardly and beneath the same when inserted within said compartments. While said retaining members 12 are convenient, I 30 do not necessarily limit my invention to their employment, since they, *per se*, may not only be widely varied in mechanical form and arrangement, but may also be omitted entirely, and in such case, the compacts secured by 35 cementitious substance or otherwise.

The compartment of each shell or body member is preferably of sufficient depth to permit of an individual powder-puff 13 for each compact to be inclosed with the latter 40 so as to be ready for use at all times.

The reference-character 14 indicates a 45 combined mirror and partition member arranged to dispose itself intermediate the respective compartments 4 and 5 when said shells or body members 2 and 3 are closed together.

Said mirror and partition member 14 conform in outline to the mouth shape or meeting ends of the shells or body-members 2 and 50 3, and the same is provided with a hinge ear 15, which projects from its periphery, and which is pivotally engaged upon the pintle of the hinge member 7, thus permitting the mirror or partition member 14 to be turned 55 over to cover either one or the other of the compartments of said shells or body-members, when the same are in opened relation. Preferably said mirror or partition member 14 comprises a plate or disk of metal highly 60 polished to provide the same with mirror-like surfaces on each side, which will readily reflect the countenance of the user of the powder-box or case. In the drawings the said mirror and partition member 14 is 65 shown to be of concavo-convex form, thus

providing on one side a concave mirror surface, and on the other a convex mirror surface, which add greatly to the convenience of the device. While said concavo-convex form of mirror and partition member involves a point of novelty and usefulness, I 70 do not entirely limit myself to the employment of such form, since it will be obvious that a straight plane surfaced member may be utilized if desired. Furthermore, I do 75 not limit myself to the employment necessarily of the plate or disk form of mirror or partition member 14, as above described, since I may employ ordinary glass mirrors 80 16 (see Fig. 5), supported by a suitable binding frame 17, having a hinge ear 18 for connecting the same pivotally upon the pintle of the hinge member 7, so that in such form the substantial interrelation of the same to the respective shell or body members will be 85 retained, and the general purposes of the same in the combination carried out in substantially the same manner as carried out by the preferred construction.

From the above description it will be apparent that the present invention provides a very neat, attractive and compact double compartment face-powder and rouge case, which may not only be rendered very ornamental in appearance, but which embodies 95 in small space every convenience to the user; and the same may be carried in the hand bag of the user without danger of the escape 100 thereof from the materials contained therein.

I am aware that some changes may be 100 made in the general arrangements and combinations of the several devices and parts, as well as in the details of the construction thereof, without departing from the scope 105 of the invention as set forth in the foregoing specification, and as defined in the appended claims. Hence, I do not limit my invention to the exact arrangements and combinations of the said devices and parts as described in said specification, nor do I confine myself to the exact details of the construction of said parts, as illustrated in the 110 accompanying drawings.

I claim:—

1. A double compartment powder-box 115 comprising a lower shell providing one compact-receiving compartment, an upper shell providing the other compact-receiving compartment, a hinge means pivotally interconnecting said shells so that the same may be 120 mutually closed one upon another, and said lower shell having an inwardly off-set vertical flange portion adapted to telescope into the mouth of the upper shell when said shells are closed together.

2. A double compartment powder-box comprising a lower shell providing one compact-receiving compartment, an upper shell providing the other compact-receiving compartment, a hinge means pivotally inter- 130

connecting said shells so that the same may be mutually closed one upon another, said lower shell having an inwardly off-set vertical flange portion adapted to telescope into the mouth of the upper shell when said shells are closed together, and a single combined mirror and partition member pivotally associated with said hinge means to extend between the compartments and within said shells when the latter are closed together.

3. A double compartment powder-box comprising a lower shell providing one compact-receiving compartment, an upper shell providing the other compact-receiving compartment, a hinge means pivotally interconnecting said shells so that the same may be mutually closed one upon another, said lower shell having an inwardly off-set vertical flange portion adapted to telescope into the mouth of the upper shell when said shells are closed together, a combined mirror and partition member pivotally associated with said hinge means to extend between the compartments of said shells when the latter are closed together, and each compartment having retaining means adapted to engage

and hold powder and rouge compacts respectively in said compartments.

4. A double compartment powder-box 30 comprising a lower shell providing one compact-receiving compartment, an upper shell providing the other compact-receiving compartment, a hinge means pivotally interconnecting said shells so that the same may 35 be mutually closed one upon another, said lower shell having an inwardly off-set vertical flange portion adapted to telescope into the mouth of the upper shell when said shells are closed together, a combined 40 mirror and partition member pivotally associated with said hinge means to extend between the compartments of said shells when the latter are closed together, said mirror and partition member being of con- 45 cavo-convex shape.

In testimony that I claim the invention set forth above I have hereunto set my hand this 2nd day of July, 1920.

GEORGE H. HARMAN.
